UNITED STATES PATENT OFFICE.

ISAAC BASHORE, OF WALLA WALLA, WASHINGTON TERRITORY.

AUTOMATIC ARTIFICIAL FINGER.

SPECIFICATION forming part of Letters Patent No. 319,776, dated June 9, 1885.

Application filed March 3, 1885. (No model.)

To all whom it may concern:

Be it known that I, ISAAC BASHORE, a citizen of the United States, of Walla Walla, in the county of Walla Walla and Territory of 5 Washington, have invented a certain new and useful Automatic Artificial Finger, of which the following is a specification.

The object of my invention is to supply defective or maimed hands with artificial fingers.

My invention consists in a jointed artificial finger attached to a hand-socket, and made to adjustably open or close by a series of arms, levers, a ratchet and dog, all operated by a 15 rock-shaft in the hand-socket, the said rock-shaft being actuated by a short working ring or socket attached to the hand-socket, and adapted to engage with the stub of any remaining finger or the thumb of the same hand, or 20 with a whole finger or thumb.

In the drawings, Figure 1 is a side view of the finger and hand-socket. Fig. 2 is a plan view of the hand and working sockets and the finger. Fig. 3 is a back view showing clearly 25 the rock-shaft and the manner of operating it. Fig. 4 is a vertical section of the hand-socket and the finger, showing the mechanism inclosed in the latter.

Like letters refer to like parts.

30 X represents the hand-socket; B, the working socket or ring for the stub of the thumb or finger remaining on the hand, and Y the artificial finger. The socket B is pivotally attached to the socket X by a link, T. On 35 the other side is an arm, C, to which is pivoted a lever, A, extending to one end of the rock-shaft D, supported within the hand-socket by cleats a a. The jointed finger Y is attached to the hand-socket by T-headed 40 guides F F, which have free play in slot E, made in the end of socket X. As the shaft D rocks, a toggle-joint or lever, H I K, actuates a ratchet, L, in connection with which there is a pivoted dog, N. (See Fig. 4.) The 45 moving ratchet lifts a lever, G, pivoted to its extension, and an eye, t, in the socket X, said lever passing through a narrow slot in the latter. As the second joint is flexed, a transverse pin, P, operates a lever, O, pivoted to a V-shaped piece, R, riveted at S S to the third joint. Thus the movement of the second joint 50 operates the third correspondingly, as the case may be.

Although but one artificial finger is shown, 55 it is evident that more can be attached to the

hand-socket, and be easily operated by the rock-shaft D and socket B.

The special purpose of the ratchet and dog is to lock the finger in any desired position until released by the further movement of 60 the rock-shaft, which is of great importance practically.

All the joints are made in a suitable form to fit close together and work easily, and the hand-socket and finger or fingers may be made 65 to suit individual requirements.

The operation of the device is briefly as follows: The finger or stub remaining on the hand is placed in the socket B, and the hand-socket fitted to the hand. Then by opening 70 or closing the hand naturally, the metal or artificial finger is correspondingly opened or closed—that is, by bringing the socket B toward the palm of the hand the rock-shaft raises all the levers in the artificial finger, 75 and causes it to close, the ratchet and dog holding it in the desired position. By an opposite movement of socket B the said levers are made to drop and the finger opens.

Having fully described my invention, what I 80 claim, and desire to secure by Letters Patent, is—

1. The combination, with the hand-socket and its rock-shaft, of the working-socket adapted to fit over a remaining member of 85 the hand and operate said shaft, and the jointed artificial finger having internal mechanism, substantially as described, whereby said finger is adjustably opened or closed by the operating of the working-socket and rock-shaft, as set forth.

2. In the artificial finger operated from without, substantially as described, the combination, with the toggle-lever, of the ratchet and dog, a lever extending from the ratchet 95 to the hand-socket, and a lever attached to the second joint, adapted to bend the third joint by the moving of the second, as set forth.

3. The working-socket B, having links T C and lever A, combined with the hand-socket 100 X, having rock-shaft D, the jointed artificial finger Y, having the guides F F, the toggle-lever H I K, the ratchet and dog L N, the lever G, the pin P in the second joint, the lever O, and the piece R, riveted to the third 105 joint at S S, as set forth.

ISAAC BASHORE.
